UNITED STATES PATENT OFFICE.

GEROLAMO CATANZANO, OF SOMERVILLE, MASSACHUSETTS.

PROPELLER.

1,380,093.

Specification of Letters Patent. Patented May 31, 1921.

Original application filed January 17, 1919, Serial No. 271,684. Divided and this application filed June 26, 1919. Serial No. 307,006.

To all whom it may concern:

Be it known that I, GEROLAMO CATANZANO, a citizen of the United States, and resident of Somerville, county of Middlesex, 5 and Commonwealth of Massachusetts, have invented an Improvement in Propellers, of which the following description, in connection with the accompanying drawings, is a specification, like characters on the drawings representing like parts.

This invention relates to propellers and aims to provide an improved construction having among others the advantages herein-after set forth and claimed.

15 This application is, in part, a division of my application Serial No. 271,684, filed January 17, 1919.

In the drawings,

Figure 1 is a side elevation of one embodiment of my novel propeller, partly in section;

Fig. 2, a partial edge view of the hub of the propeller with one of the propeller blades in position thereon;

25 Fig. 3, a side elevation of one of the blades;

Fig. 4, a detail of the blade adjusting means;

Fig. 5, a bottom view of a vessel's hull 30 equipped with a plurality of my novel propellers; and

Fig. 6, a section on the line 6—6 of Fig. 3.

Referring first to Figs. 1, 2, my novel propeller, as illustrated, comprises a relatively large and, for lightness, preferably hollow hub 1, provided with a plurality of blades 2, each suitably mounted upon or integral with a base 3.

This type of propeller is particularly 40 adapted for installation on a hull in advance of the stern as suggested in my issued Patent No. 636,488, where propellers of the common type cannot be used, and it possesses all the advantages of the construction 45 shown in that patent besides others to be described.

In my patent above noted, the blades are flat and substantially regular in outline. I have discovered that a blade fashioned approximately as shown in Figs. 2, 3, possesses 50 very superior propelling power when compared with a flat blade of substantially the same area as shown in my patent referred to.

In propellers of the common screw type 55 the blades are relatively long, narrow and

twisted progressively toward the hub in order to obtain the continued pushing effect against the water.

But as the blades approach the relatively small hub they are necessarily narrowed 60 with a decreased effective pushing area, and thus a large proportion of the effectiveness of each blade is lost. It is generally considered by those skilled in the art of designing and constructing propellers, that, for the 65 above reason, the conventional propeller blade is only about thirty-five per cent. efficient.

This disadvantage is overcome almost entirely by the use of my novel propeller, 70 wherein owing to their relatively remote distance from the center of the hub or shaft, the number of blades may be many times multiplied and the effective area of each blade also relatively much increased.

The hub presents no appreciable face to create a drag, owing to the novel manner of installing the propeller as explained in my earlier Patent No. 1,317,861, dated October 7, 1919.

Now I have discovered that more power is obtained from a propeller blade if it is so fashioned that the segment of the following blade edge farthest from the center line of the blade base, that is the widest portion of 85 the following face of the blade, is nearer the outer end or tip of the blade.

Why this is so, applicant is unable to state, unless it is because the tip end of the blade traveling through a greater circle and 90 consequent distance, than the inner end, produces a greater portion of power, and hence the extension of the following blade face and edge outwardly and laterally gives additional power. Consequently my novel 95 propeller blade is so proportioned and fashioned.

Referring especially to Figs. 2, 3, I provide the blade with a forward or leading edge 4, which is somewhat convex throughout and in which the sharpest segment of curve 5, and point of greatest distance from the center line is substantially at midlength thereof.

The opposite or following edge, somewhat 105 less convex throughout, on the contrary presents its sharpest segment of curve 6, and point most remote from the center line, nearer the tip of the blade. It is so fashioned, also, that the point 7 is farther from 110

the base center 8 than any point on the opposite edge. This half of the blade is therefore slightly longer than the opposite half, but both halves are substantially equal in 5 width at the base.

The forward or thrust face 9 of the blade Fig. 2, is moreover, substantially straight at its line of junction with the base and substantially on the diametrical line, while the 10 reverse or following face 10 is convex where it meets the base to give some additional strength. The blade is obviously somewhat wider near its outer end than adjoining its base.

15 My propeller is so proportioned that the diameter of a circle touching the tips of the blades is the same as in the case of the common form of propeller for the same size boat. As I prefer to construct my propeller 20 five of the blades are usually in the water simultaneously, and they have substantially the same effective area or working surface as the usual three blades of the common type of propeller for the same size boat.

25 Therefore each additional blade over five, herein two, provides an extra working member, every inch of which is effective or propelling area, which is not true of the propeller in common use. Inasmuch as my 30 novel blade is relatively short, it can also be made much thinner and lighter than usual. With the broad base, the blade may also be and is relatively broad at its base line, which aids in increasing the working 35 area. I have discovered that a blade fashioned as shown herewith is much more powerful or has more propelling force than a flat one such as shown in my Patent No. 636,488.

40 With the additional working surface, the relative cost per horse power is much reduced, probably as least twenty-five per cent.

45 My invention also contemplates the provision of a universal propeller and a novel method of mounting the blades upon the hub, to wit, in such manner that they may be adjusted thereon for the purpose of providing either the usual forward or back 50 pulsion of the vessel, and also the lateral movement of the vessel when desirable.

To that end I prefer to make the base, Fig. 2, elongated in outline, the narrow rear end 11 being pivoted, as by a bolt 12, to the 55 edge of the hub, while the wider outer end is slotted at 13 to receive a pin 14 extended radially from a locking and adjusting ring 15. Additional posts 12^a are provided for security to engage slots 12^b in the base 3.

60 This ring is received by a groove 15^a in the hub edge and the ring is locked in position by a locking screw 16 which engages extended lips 17 on the ends of the ring.

65 For adjusting the ring, I have provided the following novel construction.

Referring to Fig. 4, the hub shaft 18 adjacent the hub wall 19 is milled out to receive the gear 20 on the short shaft 21, which also is partly countersunk in the shaft 18 for compactness of construction. A sleeve 22 is placed over the two shafts 18, 21, and this sleeve has bearing on the wall 23 of the propeller recess in the hull.

The shaft 21 carries the handle 24 or any convenient means for rotating the shaft and 75 adjusting the blades, and of course may be locked by any suitable means, not shown.

The gear 20 meshes with a rack 25 on the ring actuating lever 26 pivoted at 27 to the hub wall 19, the upper or opposite end of 80 the lever engaging a slot 28 in the ring 15.

It will be clear that by this means the ring 15 and the several blades may be adjusted at will.

Normally the blades are positioned as 85 shown in Fig. 2, full lines. In this position the propeller will impart forward or backward motion to the vessel according to the direction of rotation.

Now it is necessary when a large vessel is 90 to dock, to have tugs on hand to turn the vessel and push her into her dock. She cannot safely undertake this with her own power.

By my adjustable or universal propeller it 95 is possible for a ship to dock herself. This is done by shifting the angle of the propeller blades to dotted line position Fig. 2 so that when revolved they will simply push the water sidewise, and thus cause the vessel to 100 move slowly sidewise or laterally to the right or left according to the direction of rotation of the propeller.

Obviously with my improved propeller 105 a vessel can approach her dock head on, and then by the effect of lateral pressure of the blades on the water push herself gently alongside the wharf with perfect safety.

It will be seen also that by providing one or more propellers fore and aft of the vessel 110 as in Fig. 5, with suitable power mechanism not shown, she may be readily moved sidewise, by simultaneous rotation of fore and aft propellers on the same side of the vessel, or by rotating the forward propellers in one 115 direction and the stern propellers in the opposite direction, the vessel may be turned around almost in her own length.

While I have herein shown one embodiment of my invention, obviously it is not 120 limited to the precise construction shown, and many modifications thereof may be made within the spirit of the invention and scope of the appended claims.

Claims:

- 125
1. A universal propeller comprising a hub with blades thereon adjustable in an arc on the outer wall of the hub, a rotatable ring on the outside of the hub, a ring actuating member connected thereto and without the 130

adjusting arc of the blades, and means operable at a point in advance of the hub for adjusting the blades.

2. A universal propeller comprising the hollow hub 1, blade bases 3 pivoted thereon for swinging adjustment, the bases having slots 12^b to receive the posts 12^a on the outer hub wall, the blade adjusting ring 15 in the groove 15^a on the hub, slots 13 in the blade bases and the pins 14 on the ring 15 extended through the slots, the ring actuator 26 pivoted to the hub and having the rack 25 thereon, a pinion 20 coöperating with the rack, and means for operating the pinion.

15 3. The combination with a hull, of a universal propeller comprising a hub, blade bases pivoted thereon, blades on the bases, a

base adjusting ring on the hub connected with the blade bases, a ring actuator on the hub, a pinion for operating the same and 20 means for operating the pinion from within the hull.

4. The combination with a hull, of a universal propeller comprising a hub, blade bases pivoted thereon, blades on the bases, a 25 base adjusting ring on the hub connected with the blade bases, a ring actuator on the hub, a pinion for operating the same, and a shaft for the pinion operable from within the hull.

In testimony whereof I have signed my name to this specification.

GEROLAMO CATANZANO.
